US00D979324S

(12) **United States Design Patent** (10) Patent No.: **US D979,324 S**
(45) Date of Patent: **** Feb. 28, 2023**

(54) **HANDLE FOR A KITCHEN UTENSIL**

(71) Applicant: **TVS S.p.A.**, Fermignano (IT)

(72) Inventor: **Giuseppe Alberto Bertozzini**,
Fermignano (IT)

(73) Assignee: **TVS S.P.A.**, Fermignano (IT)

(**) Term: **15 Years**

(21) Appl. No.: **35/512,692**

(22) Filed: **Jun. 29, 2021**

(80) **Hague Agreement Data**

Int. Filing Date: **Jun. 29, 2021**

Int. Reg. No.: **DM/216491**

Int. Reg. Date: **Jun. 29, 2021**

Int. Reg. Pub. Date: **Oct. 8, 2021**

(30) **Foreign Application Priority Data**

Dec. 29, 2020 (EM) 8373922
